LOCK SET END PLATE

Nicholas Giandomenico, West Covina, Calif., assignor to
Acme General Corporation, Monrovia, Calif.

Filed Mar. 12, 1971, Ser. No. 123,933

Term of patent 14 years

Int. Cl. D8—06

U.S. Cl. D8—139

FIG. 1

FIG. 4

FIG. 3

FIG. 1 is a perspective view of a lock set end plate constructed according to principles of this invention for mounting as the end of a door knob; shown in the environment of use as the outer face of the knob of the lock set, said knob being illustrated in broken lines for illustrative purposes only;

FIG. 2 is an end view of the lock set end plate;

FIG. 3 is a cross-section through the end plate of FIGS. 1 and 2; and

FIG. 4 is a fragmentary cross-section illustrating one of the raised portions of the end plate.

I claim:

The ornamental design for a lock set end plate, as shown and described.
